LOCKING WRENCH

William I. Truby, Cleveland Heights, Ohio

Application December 11, 1943, Serial No. 513,839

5 Claims. (Cl. 81—165)

This invention relates to wrenches of the type having relatively slidable jaw carrying members in which one of the members has a rack and the other a rotatable worm meshing with the rack by means of which the jaws may be adjusted.

The present invention has for its object to provide a means for shifting the actuating worm laterally of its axis from an operating position where it may be turned to adjust the spacing of the wrench jaw to a locking position where it presses laterally against the rack, is frictionally locked against turning movements and clamps the rack in its guideway so as to rigidly hold the jaws against relative rocking movements.

With the above and other objects in view the invention may be said to comprise the wrench illustrated in the accompanying drawing herein-after described and particularly set forth in the appended claims together with such variations and modifications thereof as will be apparent to one skilled in the art to which the invention pertains.

Reference should be had to the accompanying drawing forming a part of the specification in which;

Fig. 1 is a side elevation of the wrench showing the worm in operating position;

Fig. 2 is an elevation looking toward a side edge of the wrench;

Fig. 3 is a side elevation of the wrench with portion broken away to show the operating elements in section, the worm being shown in this view in locking engagement with the rack.

In the accompanying drawing the device of the present invention is shown applied to a wrench that has a head 1 provided with an integral jaw 2 and a guide channel 3 extending transversely of the face of the jaw 2. The guide channel 3 has an undercut guide portion 4 and the head 1 is provided with a rectangular opening 5, the top edge of which overlaps the bottom portion of the guide channel. The opening 5 has its top and bottom portions parallel with the guide channel 3 and its side edges parallel with a flat face 6 on the edge of the head 1 to which the guide channel 3 extends.

A second jaw carrying member is provided which comprises a jaw 7 and a guiding portion comprising an elongated web 8 centrally disposed with respect to the jaw 7 and having a thickened edge 9. The web 8 extends into the opening of the channel 3 and fits therein, the thickened edge 9 fitting in the undercut portion 4 of the guide channel of the head 1. The enlarged edge 9 has rack teeth 10 on the side facing the bottom

of the channel 3 and the opening 5. A shaft 11 is mounted in the head 1 and extends across the opening 5 parallel with the channel 3. The shaft 11 extends inwardly from the flat edge 6 of the head and has a threaded inner end 12 that is screwed into an internally threaded bore 13 in the head at the inner side of the opening 5. The shaft 11 is cylindrical outwardly of its threaded inner end 12 and the outer end thereof fits without a bore 14 in the head 1 outwardly of the opening 5, the outer end of the shaft 11 being substantially flush with the flat edge 6 of the head when it is secured in place.

The shaft 11 has an axial bore 15 extending inwardly from its outer end and is provided with a radial opening 16 at the inner end of the bore 15. At its inner end the shaft 11 is provided with a lateral opening 17 that is adapted to receive the end of the lock screw 18 that secures the shaft 11 in place with its lateral opening 17 facing the rack 10.

A worm 19 is rotatably mounted on the shaft 11 within the opening 5 and this worm is of a length slightly less than the width of the opening 25 and may be yieldably held against one wall of the opening by means of a spring 20. The worm 19 fits loosely on the shaft 11 so that it may have a limited lateral movement with respect to the shaft, and means is provided for shifting the worm 19 laterally with respect to the shaft 11 into clamping engagement with the rack 10 so as to lock the worm against rotation and clamp the guide portion 9 of the movable jaw carrying member in the undercut portion 4 of the guide channel so that the jaw 7 is rigidly held against pivotal movements with respect to the head 1.

Sufficient lateral pressure is applied to the worm to frictionally lock the worm against rotation and to take up any play between the sliding jaw carrying members so that the jaws are rigidly held against relative movements. A radial thrust is exerted upon the interior of the worm 40 19 at its inner end by means of a bearing ball 21 that is mounted in the radial opening 16 of the shaft 11. This ball, as shown in Fig. 1, normally occupies a position wholly within the periphery of the shaft 11 and is movable radially of the shaft 11 against the interior of the worm 19 to press the worm against the rack 10 as shown in Fig. 3. The bore of the worm 19 is preferably tapered toward its outer end allowing sufficient lateral play at the inner end thereof to enable the worm to tilt sufficiently to tightly clamp the rack 10 and jaw 7 as shown in Fig. 3. Radial

movement is imparted to the ball 21 by means of a member movable axially in the bore 15 of the shaft 11 such as a small ball 22. The ball 22 is engaged by the inner end of a screw 23 that is screwed into an internally threaded outer portion 24 of the bore 15 and which has a knurled head 25 which may be turned to adjust the screw 23 inwardly or outwardly.

When the screw 23 is in the position shown in Fig. 1, the ball 22 is retracted far enough to allow the ball 21 to occupy a position entirely within the periphery of the shaft 11. When the screw 21 is moved inwardly, the ball 22 is forced to the position shown in Fig. 3 and by its wedging engagement with the ball 21 presses the same outwardly against the interior of the worm 19 crowding the worm against the rack 10 to lock the worm and clamp the sliding jaw. The balls 21 and 22 are standard bearing balls of sizes commonly used in ball bearings and either or both balls may be easily replaced if damaged.

In order to prevent removal of the screw 23 and to limit the extent of axial movement thereof, a guard 26 is detachably secured to the edge 6 of the head by means of a screw 27 and is provided with a projecting lip 28 that overhangs the outer face of the head 25 to limit the outward movement of the screw.

By the use of hardened steel balls for applying a lateral thrust to the worm 19, a very effective clamping pressure may be applied by means of the screw 23, and since only a slight movement of the screw is required to shift the worm from its operating to clamping position, the wrench may be quickly and easily locked in any adjustment and the worm may be quickly released to permit it to be turned to change the adjustment when desired.

It is to be understood that variations and modifications of the specific device herein shown and described for purposes of illustration, may be made without departing from the spirit of the invention.

What I claim is:

1. A wrench comprising a jaw carrying member having a rack and guide portions parallel to the rack, a second jaw carrying member having a guideway to receive the guide portions of the first member, a shaft mounted in fixed position in said second member parallel to said guideway and having an opening facing said guideway, a worm loosely and rotatably mounted on said shaft and meshing with said rack, a member mounted in said shaft within said worm for radial movement in said opening toward said rack, and means for actuating said member to engage the same with the interior of the worm and press said worm against said rack.

2. A wrench comprising a jaw carrying member having a rack and guide portions parallel to the rack, a second jaw carrying member having a guideway to receive the guide portions of the first member, a shaft mounted in fixed position in said second member parallel to said guideway and having an opening facing said guideway, a worm loosely and rotatably mounted on said shaft and meshing with said rack, a member mounted in said shaft within said worm for radial movement in said opening toward said rack, and a member mounted for axial move-

ment in said shaft and engageable with said radially movable member to press the same outwardly against the interior of said worm.

3. A wrench comprising a jaw carrying member having a rack and guide portions parallel to the rack, a second jaw carrying member having a guideway to receive the guide portions of the first member, a shaft mounted in said second member parallel to said guideway, said shaft having an axial bore and a lateral opening to said bore, means for securing said shaft against rotation with said opening facing said guideway, a worm loosely and rotatably mounted upon the portion of said shaft in which said opening is located and meshing with said rack, a ball mounted in said opening and movable from a position in which it is entirely within the periphery of the shaft and partially within said bore to a position in which it extends beyond the periphery of said shaft and presses said worm against said rack, and a member movable axially of said bore and engageable with said ball to move the same radially outwardly against the interior of said worm.

4. A wrench comprising a jaw carrying member having a rack and guide portions parallel to the rack, a second jaw carrying member having a guideway to receive the guide portions of the first member, a shaft mounted in said second member parallel to said guideway, said shaft having an axial bore and a lateral opening to said bore, means for securing said shaft against rotation with said opening facing said guideway, a worm loosely and rotatably mounted upon the portion of said shaft in which said opening is located and meshing with said rack, a ball mounted in said opening and movable from a position in which it is entirely within the periphery of the shaft and partially within said bore to a position in which it extends beyond the periphery of said shaft and presses said worm against said rack, a second ball movable axially in said bore and engaging the first ball, and a screw for pressing said second ball axially of said shaft.

5. A wrench having a head provided with a jaw, an undercut guide channel extending transversely of the jaw, and a transverse opening intersecting the bottom of said channel, a movable member having a jaw and a guide portion slideable in said channel and having rack teeth in the side thereof facing the bottom of the channel, a shaft mounted in said head and extending across said opening parallel with said guideway, said shaft having an axial bore and a lateral opening to said bore, means for securing said shaft against rotation with its lateral opening in the opening of the head and facing said rack, a worm rotatably and loosely mounted on said shaft within the opening of the head, a ball mounted for radial movement in the lateral opening of the shaft from a position entirely within the shaft to a position bearing against the interior of the worm, and means for applying a radial pressure to said ball to press said worm into locking engagement with said rack comprising an axially movable screw extending into the bore of said shaft.

WILLIAM I. TRUBY.
